DESIGN FOR A KNITTED TEXTILE FABRIC

Adolph Lehmann, New York, N. Y.

Application February 16, 1942, Serial No. 105,830

Term of patent 3½ years

To all whom it may concern:

Be it known that I, Adolph Lehmann, a citizen of the United States, residing in New York city, in the county of New York and State of New York, have invented a new, original, and ornamental Design for a Knitted Textile Fabric, of which the following is a specification, reference being had to the accompanying drawing, forming part thereof.

The figure is a plan view of a knitted textile fabric showing my new design.

I claim:

The ornamental design for a knitted textile fabric, substantially as shown.

ADOLPH LEHMANN.
